INTERFITTING LOCK FOR CONTAINERS

George E. Wauda, Neenah, Wis., assignor to
 Marathon Corporation, Rothschild, Wis., a corporation of Wisconsin

Application March 14, 1949, Serial No. 81,256

1 Claim. (Cl. 229—35)

1
 This invention relates to a collapsible container or box and more particularly to an improved locking means for locking together wall portions of such containers or boxes.

The principal object of this invention is to provide a container which can be formed from a blank preferably from relatively stiff material such as paper board by automatic packaging equipment. It is a further object to provide locking connections between portions of said blank which require no adhesive when forming the blank into a container. It is still a further object to provide a locking connection which is so designed so as to have a high resistance against opening even when relatively thin flexible materials and particularly laminated materials are used and it is yet another object to provide a locking connection which is sufficiently flexible to insure rapid locking by mechanical means without loss of wall strength in the finished container.

Other objects and advantages of my invention will appear from the following description, including the drawings forming a part thereof, and wherein like numerals are used for like parts in each of the figures, of trays incorporating my improved locking means.

Figure 1 is a plan view of a container or tray of my invention in blank or collapsed form.

Figure 2 is a front perspective view showing one end of my container partially set up.

Figure 3 is a fragmentary plan perspective view showing in more detail the relative position of the parts of my locking device in Figure 2.

Figure 4 is similar to Figure 3 with the carton fully set up.

Figure 5 is a fragmentary plan view showing the relative position of the parts of my locking device in set up position.

Figure 6 is a front perspective of my completed container.

Figure 7 is a fragmentary plan view of a tray in the blank or knocked down form having a modified locking device of my invention.

Figure 8 is similar to Figure 2 showing my modified locking device.

Figure 9 is similar to Figure 3 showing my modified locking device.

Figure 10 is similar to Figure 4 showing my modified locking device.

Figure 11 is a partial front perspective view of the finished container of Figure 7.

Figure 12 is a fragmentary plan view of the tray in Figure 1 in the blank showing still another modification of the locking device.

2
 The blank of Figure 1 is suitably cut and scored in the conventional manner to provide a bottom wall 1 to which is hingedly connected along score lines 2 and 3 side walls 4 and 5 and along score lines 6 and 7 side or end walls 8 and 9. To the end wall 8 hingedly connected by score lines 10 and 11 forming the edges of end wall 8 are flaps 12 and 13. Similarly hingedly connected to end wall 9 by score lines 14 and 15 are flaps 16 and 17.

In setting up a container from the blank in Figure 1 the walls 4, 5, 8 and 9 are all folded upwardly to a position at right angles to the bottom wall 1 and the flaps 12, 13, 16 and 17 are then folded at right angles to walls 8 and 9 so as to overlie portions of walls 4 and 5 all as is conventional in setting up collapsible types of cartons or containers. To maintain the relative parts of the container in the position described locking means are provided between adjacent side walls and where it is desired not to use adhesives such locking means usually provide a tongue on one member which engages a slit on the other member.

The improved locking means of my container, which I shall describe with respect to one corner thereof since each of the corners is identical, comprises a slit 20 which is cut in the side wall 4 and a cooperating tongue 21 which is integral with and formed from flap 16. In the modification of my container in Figure 1 the slit 20 comprises a straight section 22 which extends upwardly from the score line 2 and inwardly from the edge 23 of the side wall 4 for a distance substantially mid-way up the side wall and a second straight slit 24 joining slit 22 which extends further upwardly in the side wall 4 and preferably is cut at an angle of substantially 45° to score line 2, that is, to the bottom of the container. Slit 24 terminates short of the top edge 25 of side wall 4. The proximity of the end of the slit 24 and edge 25 is determined solely by the strength required in the lock since the material in the side wall therebetween determines the strength of the lock.

The tongue 21 may be considered as being in two parts. One part is the slit engaging portion 26, which preferably but not necessarily extends beyond the front edge of flap 16, having a top edge 27 and a bottom edge 28. Edge 28 is a continuation of the bottom edge of flap 16. The other part of the tongue is referred to as the hinge portion 29 and is formed in the lower portion of flap 16 by a slit 30 cut back into the body 50 of the flap from the front edge 31. Preferably

3

the slit 30 is a continuation of the top edge 27 of portion 26 of the tongue. Edge 27 in turn is preferably cut at substantially the same angle as portion 24 of slit 20 which it ultimately engages. In the embodiment shown this angle is substantially 45° to the bottom edge 28.

The slit 30 terminates short of the bottom edge 28 of the flap and also short of the score line 14, its actual length being determined by the degree of flexibility desired in the tongue and the strength requirements of the tongue depending upon the material from which the carton is made. The strength of the tongue is of course determined by the amount of material between the end of the slit 30 and the bottom edge 28 of the flap. It should be noted that the edge 28 is a straight edge formed by a slit which is in substantial alinement with score line 7.

Referring now to Figures 2, 3, 4 and 5, after the slit 20 has been partially opened by mechanical devices in the automatic packaging machine in which my container is to be set up, the tongue 21 is inserted into the slit. In the position shown in Figures 2 and 3 it will be noted that the distortion in the slit due to the insertion of the tongue sets up forces due to the inherent resiliency of the material. For example, in Figure 3 the area adjacent the slit as indicated by 35 has been extended outwardly and hence tends to exert a force inwardly on the tongue 21. The portion of the wall 4 as indicated in 36 has been distorted inwardly by the flap 16 and hence it tends to cause the flap to be bowed outwardly. The distortion between the flap and the side wall is due to the fact that score line 14 and score line 2 are substantially in alinement. As the tongue is further inserted in the slit 20 to the point where the edge 27 of the tongue is below or in alinement with the upper portion 24 of slit 20 the pressure of the wall portion 35 is greater than the resistance of the flexible tongue and hence, the tongue is snapped inwardly to effect engagement of the edge 27 with the locking portion of the slit 24. This snapping in of the tongue is effectively accentuated first by the increased flexibility of the tongue due to its great effective length and by the fact that the portion 39 of the flap 16, which lies above the tongue, that is above the slit 30, is still being urged outwardly by the distortion of the wall portion 36. In prior devices that I have known where the tongue is merely an extension of a flap, there is not the combination of forces present which I have found make my locking means more effective in automatic machinery. When in these prior devices there is an attempt to increase the flexibility of the tongue by extending them further beyond the edge of the flap to which they are connected there is not only a loss of strength at the junction between the flap and the side wall because of the lack of support which the flap would contribute and does contribute in my locking device, that is portion 39, but there is not the degree of opposing forces present which create a snapping action in the engagement of the tongue with the lock.

Figure 5 more clearly shows that the effective length of the tongue in my locking device extends from a point 37 which is determined by the end of slit 30 to the front edge of the tongue and that the portion 39 of the flap 16 which is above the slit 30 overlies the side wall 4 and hence contributes strength to the carton at a point where it would otherwise be weakened by the presence of the slit 20.

It was previously pointed out the upper portion 24 of slit 20 and the top edge 27 of my locking tongue 21 form an approximately equal angle substantially e. g. 45° with the bottom of the container and hence when the tongue is in locking position these two edges coincide. My lock is greatly strengthened by this fact since it does not depend on its locking strength for single point contact. In some applications, however, I prefer to have the relative angle of my tongue and slit, and the flexibility of my tongue, such that the lock takes place in the crotch formed by the tongue and the flap. This is particularly desirable when using laminated board stock. My lock is further strengthened by the fact that when in locking position the bottom edge 28 of the locking flap substantially rests on the bottom wall 1 of my container and hence supports the side or end wall 9 against any inward pressure which would otherwise only be resisted by the abutment of the side wall 4 with the end of side wall 5. It is seen that this strut action of the flap 16 is only made possible by the extension of slit 28 to the score line 2. Previous attempts of which I am aware to obtain strut action by cutting out a portion of the bottom edge of the flap to provide a front foot which would pass through a slit which would not extend to the score line but which would rest on the bottom wall of a container have not come into use because of the practically impossibility of manufacture and inherent weakness when adapted to small sized containers.

In the embodiment of my invention of Figure 7 through 11 I have shown another form of locking slit which has certain advantages depending upon the type of mechanical apparatus used to effect the opening thereof. In all other respects the parts are the same as those in Figure 1 and like numerals have been used for like parts throughout.

The slit 40 in the container in Figure 7 in side wall 4 comprises a single straight slit 41 extending upwardly from the score line 2 and outwardly from the edge 23 of the side wall preferably at an angle of substantially 45° to score line 2 or the bottom wall 1 of the container. The slit 41 terminates below the top edge 25 of the side wall 4 and the distance below is determined in the same manner as was described for the container of Figures 1 through 6. Substantially mid-way along the length of slit 41 is a second slit 42 which intercepts slit 41 at substantially right angles. The slit 42 serves to weaken the area of the side wall which is distorted inwardly by the action of the tongue so as to facilitate entrance of the tongue into the slit. It will be seen in Figures 8 and 9, however, that the portion 43 of the side wall below the slit is unbroken and hence will exert a pressure inwardly on the tongue to effectuate the locking action previously described. It will readily be seen also that by forming the tongue from the flap 16 through slit 30 I have made available portion 39 of flap 16 for overlying a greater portion of the area of side wall 4 which has been weakened by slit 42. Where mechanical equipment is so designed that the slit 40 can be opened sufficiently to permit the insertion of the tongue without including in slit 41 the additional slit 42, this slit may be dispensed with without losing the advantages of my improved locking means such as the line locking action obtained by having edge 27 and slit 41 both cut 75 at the substantially same angle to the bottom

wall 1, the strut action obtained by having slit 41 extend from the score line 2, and the increased flexibility of my tongue without the loss of strength due to forming the tongue from flap 16 by slit 30.

Another modification in the structure of the locking tongue which is particularly useful when using thick board is shown in Figure 12. This modified tongue structure is shown in relation to the tray of Figure 1 though it will be readily understood that tray of Figure 7 could also be so modified. In this modification I provide a hinge for the tongue in the form of a vertical score line 50 extending from the end of slit 30 down to the bottom edge 28. Obviously each of the tongues could be so modified in either tray shown.

It is appreciated that though I have shown various modifications of my improved locking means in connection with a tray type of container various of its advantages will be obtained when locking walls together in other forms of collapsible containers which conventionally use tongue and slit locking devices, therefore, no limitations are intended by the above description except such as are contained in the following claim.

I claim:

In a carton a bottom wall, at least two adjacent side walls at substantial right angles to each other, a locking flap connected to one of the contiguous edges of one of said side walls and adapted to overlie a portion of said other side wall and having a front edge opposite its connection to said one side wall, a slit cut in said

other side wall extending from the base of said wall upwardly and angularly away from the edge of said wall to a point below the upper edge thereof at least the upper portion of said slit 5 being disposed at about 45° angle to the base of said wall and a locking tongue integral with and formed from said flap and extending forwardly from the bottom portion of the front edge of said flap, said tongue having a slit engaging portion extending beyond the front edge of the upper portion of said flap and having an upper edge disposed at an angle of about 45° to the base of said flap and a hinge portion partially cut out from the lower portion of said flap 10 by a slit extending rearwardly from the front edge of said flap back into the body of said flap, said slit being a straight line continuation of the top edge of said slit engaging portion.
